UNITED STATES PATENT OFFICE.

EDWARD R. YOUNG, OF NEW YORK, N. Y.

CASE FOR BOOKS.

SPECIFICATION forming part of Letters Patent No. 258,844, dated May 30, 1882.

Application filed April 21, 1882. (No model.)

To all whom it may concern:

Be it known that I, EDWARD R. YOUNG, a citizen of the United States, residing at New York, in the county and State of New York, 5 have invented new and useful Improvements in Cases for Containing and Carrying Books, of which the following is a specification.

This invention consists in a case formed of one piece of leather or other suitable material 10 cut out and bent to form a base and four folding flaps, the ends of which are connected by a suitable clasp, so that when the clasp is opened the flaps can be readily unfolded for the introduction or removal of books, and when the case 15 is closed it forms a safe protection for the books contained in it. A flexible handle serves to carry the case with its contents.

In the accompanying drawings, Figure 1 represents a perspective view of my case when 20 closed. Fig. 2 is a transverse section of the same. Fig. 3 is a plan of the case when unfolded.

Similar letters indicate corresponding parts. In the drawings, the letter A designates my 25 case, which is formed of a single piece of leather or other suitable material cut out, as shown in Fig. 3. By inspecting this figure it will be seen that said piece forms a base, a, and four flaps, b b' b² b³, each of which is folded twice, as indicated by dotted lines c c*, c' c'*, c² c^{2*}, c³ c^{3*}. In the ends of the flaps b' b² b³ are formed eyelet-holes, d, and to the flap b is firmly secured a clasp, B, Figs. 1 and 2, which is provided with a stud, e, to engage with the eyelet-holes d 35 of the flaps b' b² b³, as shown in Fig. 2. The

spaces between the folds c c*, c' c'*, c² c^{2*}, and c³ c^{3*} are all alike, and they correspond to the thickness of the book or books to be carried in the case A, while the base a is equal in size and shape to the surface of the book or books, 40 so that when said book or books are placed on the base a the flaps b, b', b², and b³ can be folded down in order named, and if the eyelet-holes of the flaps b' b² b³ are made to engage with the stud e of the clasp, and the cover of said 45 clasp is turned down, as shown in Fig. 2, all the flaps are firmly retained in position, and the case forms an envelope for the books.

To one of the flaps (b², for instance) is secured a handle, C, which serves to carry the 50 case with its contents.

When the book or books are taken out of the case A said case can be folded up into a small compass for transportation or to be carried in the pocket. 55

What I claim as new, and desire to secure by Letters Patent, is—

As an improved article of manufacture, a case for carrying books, composed of a base, a, folding flaps b b' b² b³, eyelet-holes in the flaps b' b² b³, a clasp secured to the flap b, and a handle for carrying the case, all as shown and described. 60

In testimony whereof I have hereunto set my hand and seal in the presence of two sub- 65 scribing witnesses.

EDWARD R. YOUNG. [L. S.]
